DESIGN FOR A FRUIT JUICER

Jean Otis Reinecke, Oak Park, Ill., assignor to Dazey Churn and Manufacturing Company, St.
Louis, Mo., a corporation of Missouri

Application June 7, 1941, Serial No. 101,342

Term of patent 7 years

To all whom it may concern:

Be it known that I, Jean Otis Reinecke, a citizen of the United States, residing in the city of Oak Park, county of Cook, and State of Illinois, have invented a new, original, and ornamental Design for a Fruit Juicer, of which the following is a specification, reference being had to the accompanying drawing forming a part thereof, in which

Fig. 1 is a top plan view of a fruit juicer embodying my new design, and Fig. 2 is a side elevational view thereof.

I claim:

The ornamental design for a fruit juicer, substantially as shown.

JEAN OTIS REINECKE.
